INVENTOR
Vernon C. Snyder

UNITED STATES PATENT OFFICE.

VERNON C. SNYDER, OF MOUNTAIN LAKES, NEW JERSEY.

CONTAINER.

Application filed September 22, 1921. Serial No. 502,521.

To all whom it may concern:

Be it known that I, VERNON CHARLES SNYDER, residing at Mountain Lakes, in the county of Morris, State of New Jersey, have 5 invented certain new and useful Improvements in Containers; and I do hereby declare the following to be a full, clear, and exact description of the invention, such as will enable others skilled in the art to which it 10 appertains to make and use the same.

My invention refers to improvements in containers which may be used for cereals, drugs, chemicals, tobacco, salt, coffee and other materials which may be kept in a paper 15 or fiber receptacle.

The particular object of the invention is to provide a container having a metal top made in such a manner that it will serve as an effective seal for the closed container and 20 as a convenient and tight cover for said container after it has been opened by cutting the wall around the edge of said metal top. The cylindrical portion of the container may be made of paper or fiber either impregnated 25 or not depending upon the nature of the material to be placed therein. The bottom of said container may be made of material similar to that composing the cylindrical portion or of metal, said bottom being attached to the cylindrical portion in any suitable manner.

In the accompanying drawings—

Fig. 1 is a sectional view of the sealed container;

Fig. 2 is a perspective view of the container with the top removed;

Fig. 3 is an enlarged sectional view of a portion of the container showing the method of opening said container;

Fig. 4 is an enlarged sectional view of a portion of the container showing the top removed.

Fig. 5 is an enlarged sectional view of a portion of the container showing the cover slipped in place prior to crimping the outer portion thereof, and

Fig. 6 is a view similar to Fig. 5 but showing the lower edge of the outer portion of the cover crimped so as to hold the cover in place.

Referring to the drawings by numerals, 1 represents the container wall, 2 the bottom and 3 the top of said container.

The method of making the top, 3, can be 55 explained by referring to Fig. 3. A depres-

sion is made in a circular piece of sheet metal—the bottom of the depression is shown at 4 and the top at 5. A groove 6 is then made in the cover, the container is then filled, the cover placed thereon and the outer 60 edge 7 of said cover crimped to form a tight seal with the container wall.

A more effective seal may be obtained by filling the groove 6 with paraffin or other suitable sealing material depending upon 65 the nature of the material to be placed in the container. The outer portion 7 of the cover is then crimped forcing the container wall into the groove.

The container is opened by inserting a 70 knife shown at 9 into the groove 6 through the container wall and then cutting around the periphery of the cover so that it may be removed as shown in Figs. 2 and 4, a portion 8 of the container wall being retained 75 in the cover and forming a part thereof. The purpose of the groove 6 is to facilitate the cutting of the container wall and, together with the crimp portion 7, to serve as a guide for the knife so that a 80 straight cut may be made and an even surface 10 produced. It is apparent that the groove 6 should be about even with the lower edge of the crimped portion 7.

In Figs. 5 and 6 there is illustrated the 85 manner in which the cover is applied to the end of the container. In Fig. 5 the groove 6 is shown as filled with the sealing material 11 such as paraffin, and with this material in place within the groove the cover 90 is slipped over the end of the container. Thereafter the lower rim 12 of the outer portion 7 of the cover is crimped or forced 95 inwardly as illustrated, thus forcing the material of the container into the groove 95 to a slight extent, the portion of the container so affected cooperating with the sealing material to form a tight seal.

In the drawing the cylindrical wall 1 of the container is shown as being right circular. However, this invention may be embodied in a container, the horizontal section of which is not circular and the invention is accordingly not limited in this respect.

I claim:

1. A container of the type shown having a metal top crimped to the wall thereof and means provided in said top whereby it may be removed, said top serving as a removable 100 tight cover for the container.

105

110

2. A container of the type shown having a recessed metal top, means whereby said top may be secured to said container, and a groove extending around the periphery of the recessed portion of said metal top, the periphery of said top being formed as a flange lying parallel to the outer wall of the recess with the marginal edge of this flange terminating opposite said groove. 25
- 10 3. A container of the type shown having a recessed metal top crimped to the container wall, a groove extending around the periphery of the recessed portion of said top whereby the top may be removed by inserting a tool into said groove and cutting the container wall peripherally. 30
- 15 4. A metal top for a container of the type shown, having a recessed portion fitting tightly against the inner surface of the container wall, said top being crimped to said wall, a groove extending around the periphery of said recessed portion whereby the container may be opened by inserting a tool 35
- 20 into said groove and cutting the container wall peripherally. 40
5. A container of the type shown having a recessed metal top fitting tightly against the inner surface of the container wall, a groove extending around the periphery of the recessed portion of said top, the marginal edge of the outer portion of said top terminating adjacent said groove and being crimped into the outer surface of the container wall forcing said wall into said groove.
6. A container of the type shown having a recessed metal top fitting tightly against the inner surface of the container wall, a groove extending around the periphery of the recessed portion of said top, a suitable sealing material in said groove, the marginal edge of the outer portion of said top being crimped into the outer surface of the container wall forcing the wall into said groove.

In testimony whereof I affix my signature.

VERNON C. SNYDER.
